UNITED STATES PATENT OFFICE.

WILLIAM H. PEADEN, OF TULSA, OKLAHOMA, ASSIGNOR TO R. D. DONNELLY AND
B. R. GRAHAM, BOTH OF TULSA, OKLAHOMA.

FAUCET.

Application filed March 14, 1927. Serial No. 175,266.

This invention relates to valves or faucets such as are used for coffee urns, dispensing receptacles, tanks, and in a large variety of other circumstances.

5 The general object of the invention is to provide a faucet having a discharge spout which is normally turned up in an inoperative position but which may be turned so as to discharge downward and provide this 10 spout with an interior valve construction such that when the spout is turned downward, the spout may be longitudinally shifted to open the valve but that when the spout is turned upward the spout cannot 15 be longitudinally shifted to open the valve.

A further object is to provide a lever or handle on the spout by which it may be axially rotated and by which when the spout is turned to its discharge position, the spout 20 may be longitudinally shifted to open the valve, said handle further affording means whereby the spout may be locked in its inoperative position.

Another object in this connection is to 25 provide a closure which covers the open end of the spout when the spout is turned upward.

My invention is illustrated in the accompanying drawings wherein:—

30 Figure 1 is a vertical sectional view of a faucet constructed in accordance with my invention, the spout being in its inoperative position;

Fig. 2 is a like view to Figure 1 but showing the spout in an inoperative position and showing it forced inward in dotted lines;

Fig. 3 is an end view of the spout.

Referring to these drawings 10 designates the body of the valve or faucet which is screw-threadedly engaged or otherwise engaged with the container or vessel from which the liquid is to be discharged. This body adjacent its inner end is formed with the valve seat 11 having a centrally and outwardly inclined seating face 12. The body is also provided with a packing ring or gasket 13.

50 Operating within the outer end of the body is the inner cylindrical end of an angular spout 14. This spout is rotatable within the body and longitudinally shiftable within the body. The inner end of the spout carries a spider 15 and having screw-threaded engagement with this spider or 55 otherwise engaged therewith is the longi-

tudinally extending stem 16 carrying the valve 17 coacting with the valve seat 12. A spring 18 bears at one end against the valve seat and at the other end against the adjacent end of the spout and urges the 60 spout outward and, therefore, urges the valve 17 against its seat.

For the purpose of rotating the spout 14 I provide the spout with an ear 19 upon which is pivoted the lever or handle 20. 65 This handle is pivoted for movement parallel to the axis of the body 10.

Carried upon the body 10 is the upwardly projecting bracket or supporting member 21 having an offset, longitudinally extending portion 22. Beyond this portion 22 the bracket extends upward and outward and supports the closure disk or equivalent element 23, which is disposed at a slight inclination to the horizontal. The inner face 75 of the offset portion 22 is formed to provide a fulcrum 24 against which the lever 20 may bear when this lever or handle 20 has been turned upward and disposed within the offset portion 22. When the handle 80 or lever is turned downward and the discharge end of the spout turned upward, the handle may be shifted upon its pivot into a position parallel to the body 10 and into engagement with a hasp 25 through 85 which a padlock may be placed.

It will be seen that with this construction the spout or discharge end of the faucet is normally turned upward so that there will be no possible chance of leakage from the 90 spout and that under these circumstances the valve 17 is closed. This valve will be held closed not only by the spring 18 but by the pressure of liquid behind the valve. When it is desired to open the faucet, the lever 95 or handle 20 is turned from a depending position to a raised position until it reaches the offset portion 22 which constitutes a stop. The discharge end of the faucet is then downward and by shifting the lever 20 in the direction of the arrow in Figure 1, the lever will rock upon the fulcrum 24, shifting the discharge portion of the faucet rearward against the action of the spring 18 and opening the valve. It will be seen 105 that the faucet cannot be opened unless the lever has been shifted. The faucet cannot be left opened accidentally as the spring 18 when pressure is released from the lever, 110 will cause the closing of the valve 17 and

this will be aided by the pressure behind it. Obviously where the device is to be used for coffee urns or like articles, the parts will be of an ornamental nature and obviously many changes might be made in the details of construction and arrangement of parts illustrated without departing from the spirit of the invention as defined in the appended claims.

10 The closure 23 prevents any dust or dirt from entering the spout 14 and also prevents ants or other insects from crawling into the spout, which often happens in the faucets used for discharging syrup and other 15 sweet liquids.

It will, of course, be noted that if the spring 18 be attached at one end to the body 10 or the seat 11 and at the other end to the spout, that the torsion of this spring will 20 resist the turning of the spout to its discharge position and will act to yieldingly urge the spout to its inoperative position.

I claim:—

1. A faucet comprising a body having a 25 valve seat and a spout rotatably and longitudinally shiftable within the body and having a valve coacting with the valve seat, and a spring acting to hold the spout shifted in a direction to cause the closing of the valve, a lever pivotally connected to the spout whereby it may be turned, and a fulcrum 30 member with which the lever coacts when the spout has been turned by the lever to a discharge position.

2. A valve or faucet of the character described including a body, an angular spout 35 rotatively mounted within the body and longitudinally shiftable therein, a valve seat on the body, a stem extending from the inner 40 end of the spout through the seat and carrying a valve, a spring urging the spout outward and the valve against the seat, a lever pivotally mounted upon the spout for movement parallel to the axis thereof, and a member mounted upon the body at the top thereof and extending across the path of movement 45 of the lever and forming a stop for the

lever when the outer end of the spout is downward, said stop member being formed to provide a fulcrum against which the lever may bear to cause the inward movement of the spout and the opening of the valve. 50

3. A valve or faucet of the character described including a body, an angular spout 55 rotatively mounted within the body and longitudinally shiftable therein, a valve seat on the body, a stem extending from the inner end of the spout through the seat and carrying a valve, a spring urging the spout outward and the valve against the seat, a lever pivotally mounted upon the spout for movement parallel to the axis thereof, and a member mounted upon the body at the top thereof and extending across the path of movement 60 of the lever and forming a stop for the lever when the outer end of the spout is downward, said stop member being formed to provide a fulcrum against which the lever may bear to cause the inward movement of the spout and the opening of the valve, the 65 stop member carrying a closure beneath which the end of the spout is disposed when the spout is turned to its inoperative position. 70

4. A faucet comprising a tubular body 75 having a valve seat and a spout having an angular discharge end, the spout being longitudinally slidable within the body and rotatable therein and having a valve rigidly mounted thereon and coacting with the valve 80 seat, a spring acting to hold the spout shifted in a direction to cause the closing of the valve, and manually operable means whereby the spout may be rotated within the body from a position with its angular end extending upward to a position with its angular end extending downward, said manually operable means in the last named position being operative to permit the spout to be shifted longitudinally to thus open the valve. 85 90

In testimony wherof I hereunto affix my signature.

WILLIAM H. PEADEN.
